CLAIM

The ornamental design for a holder for electronic devices, as shown and described.

DESCRIPTION

FIG. 1 is a front elevation view of a holder for electronic devices, showing our new design;

FIG. 2 is a left side elevation view thereof;

FIG. 3 is a top view thereof;

FIG. 4 is a bottom view thereof;

FIG. 5 is a rear elevation view thereof;

FIG. 6 is a right side elevation view thereof; and,

FIG. 7 is an upper perspective view thereof.

The dash-dash broken lines in the drawings are for the purpose of illustrating portions of the holder for electronic devices that form no part of the claimed design.

1 Claim, 7 Drawing Sheets(56)
